UNITED STATES PATENT OFFICE.

GRANVILLE H. STALLMAN, OF PHILADELPHIA, PENNSYLVANIA.

PISTON.

No. 811,255.

Specification of Letters Patent.

Patented Jan. 30, 1906.

Application filed April 6, 1905. Serial No. 254,263.

To all whom it may concern:

Be it known that I, GRANVILLE H. STALLMAN, a citizen of the United States, and a resident of the city and county of Philadelphia, State of Pennsylvania, have invented certain new and useful Improvements in Pistons, of which the following is a specification.

My invention relates to improvements in pistons, and more particularly to improvements in the self-adjusting pistons used in sausage-filling and like machines, where it is desirable to employ a single-acting rodless piston; and the object of my invention is to furnish an improvement in the construction of this class of pistons, as fully set forth hereinafter.

The accompanying drawing shows a central vertical section through a piston of my construction and a similar view of part of a cylinder in which the piston is placed.

a is the cylinder.

The piston proper is constructed in two parts, a main portion *b* and a secondary portion *c*. The main portion *b* is furnished with a head *d*, with sides *k*, and with a central web or hub *e*, the upper end of which is bored out, as shown at *f*, and the lower portion of which is drilled to receive loosely a bolt *g*, the lower end of which is adapted to be screwed into the secondary portion *c*. In order to hold the bolt *g* and the portion *c* in place, the former carries a nut or head *h*, which is adapted to rest upon the seat formed by the under side of the opening *f*.

i is a plug closing the top of the opening *f*.

The side of the secondary portion *c* that faces the main portion *b* of the piston is furnished with a flange *j*, which is adapted to pass between the cylinder *a* and the sides *k* of the main portion of the piston and to bear

against the elastic packing *l*, which surrounds the main portion of the piston, as shown, and which at its upper end bears against a shoulder *m*, formed by the head *d*.

The actuating fluid being admitted to the 45 under part of the cylinder *a* engages the under side of the portion *c* of the piston, raises it and the bolt *g*, and causes the flange *j* to engage the under end of the elastic packing *l*, which is expanded, making a perfectly tight 50 joint between the piston and cylinder. As soon as the pressure of the actuating fluid is relieved the portion *c* of the piston falls and the packing *l* contracts, permitting the piston to fall freely or to follow the actuating 55 fluid as it is drawn from the lower end of the cylinder.

I am aware that pistons have been before made with a loose portion corresponding to my portion *c* for expanding an elastic packing between the main portion of the piston and the sides of the cylinder, and hence I do not claim this feature broadly; but

What I do claim is—

In a piston, in combination, a main portion 65 consisting of a head, sides, and a central web or hub, the latter of which is bored and drilled longitudinally, a plug for closing the upper end of the bored portion of said web or hub, a movable flanged head, a bolt secured 70 to said head and passing through the drilled portion of said web, a head or nut on said bolt, and an elastic packing surrounding the main portion of said piston resting upon the flange of the movable head.

GRANVILLE H. STALLMAN.
